specification and drawings filed on the 17th day of January, 1944, Serial No. 518,498, and for the invention described in the continuation-in-part application filed on the 17th day of January, 1945, Serial No. 600,311, which applications are incorporated herein by reference.

UNITED STATES PATENT OFFICE

2,387,381

SMOKING DEVICE

Roscoe C. Zuckerman, Stockton, Calif.

Application January 17, 1944, Serial No. 518,498

1 Claim. (Cl. 131—199)

This invention relates to holders for cigars or cigarettes, or as the stem for a pipe, though for convenience the device will hereinafter be referred to generally as a holder.

The principal object is to provide a device of this character so constructed that the smoke must travel a relatively long path through the holder so that by the time it reaches the mouth of a smoker the smoke is in a very cool condition. Such long path necessitates the use of a non-straight or tortuous passage through the holder, and another object is to construct the holder so that it may be readily taken apart and said passage easily cleaned out when necessary.

A further object is to construct the holder so that the cooling action on the smoke is increased, in addition to the cooling action provided by the tortuous passage.

A further object is to construct the holder of the transparent material so that the movement and whirling action of the smoke through the holder will be visible to the onlooker.

A further object of the invention is to provide a simple and inexpensive device, and yet one which will be exceedingly effective for the purpose for which it is designed.

These objects I accomplish by means of such structure and relative arrangement of parts as will fully appear by a perusal of the following specification and claims.

In the drawing similar characters of reference indicate corresponding parts in the several views:

Figure 1 is a side elevation of a cigarette holder embodying my invention, and partly in section.

Figure 2 is an enlarged plan view of one member of the holder.

Figure 3 is a similar view of the other matching member of the holder.

Figure 4 is a cross section on the line 4—4 of Figs. 2 and 3, with the members assembled.

Figure 5 is a similar view on the line 5—5 of Figs. 2 and 3.

Figure 6 is a fragmentary elevation, mainly in section, of the invention as incorporated in a pipe stem.

Figure 7 is a fragmentary elevation showing the holder arranged to support a cigar.

Referring now more particularly to the characters of reference on the drawing, the holder comprises a pair of matching semi-cylindrical elongated members 1 and 2 having flat faces 3 throughout their extent in their diametral plane adapted to flatly engage each other when the members are assembled; said members together forming the stem on the holder.

At their opposite ends the members are reduced in diameter somewhat for a short distance, as at 4 and 5, to provide for frictional holding engagement with coupling sleeves 6 and 7 which are formed on the corresponding ends of a cigarette holding socket 8 and mouth-piece 9, respectively; the sleeve 6 being particularly of fire resistant material.

The portions 4 and 5 of the stem are provided with straight bores 10, but between said bores the stem is formed with a tortuous smoke passage communicating with said bores and arranged as follows:

Formed in each member from end to end and in matching relation in the two members is a series of closely transparent semi-circular recesses 11, cut in from the faces 3, and when said members are assembled providing full-circle smoke compartments or chambers separated by transverse walls 12. The alternate walls 12 are provided with openings or ports 13 cut in from the surface 3 at one side, while the intermediate walls are provided with similarly disposed openings or ports 14 on the opposite side. The endmost smoke chambers communicate freely with the end bores 10.

By this arrangement and when the members 1 and 2 are assembled, the bores 10, chambers 11, and ports 13 and 14 form a continuous but tortuous or zig-zag passage through which the smoke must travel between the cigarette C and the mouthpiece 9, which passage is many times longer than the stem. The smoke thus has ample time to become very cool before it reaches the mouth-piece, this cooling being aided by the formation of heat radiating ribs 15 about the exterior of the stem.

The stem is preferably made of transparent material, such as "Lucite," which not only presents an attractive appearance, but enables the passage of the smoke along the internal tortuous passage to be readily seen, the stem being formed of readily separable parts (by merely clipping off the coupling sleeves 6 and 7). The opposed portions of the chambers 11 and communicating ports are then exposed and may be easily cleaned out when necessary, as will be obvious.

In order to locate the members 1 and 2 against displacement when assembled, one member is provided with dowels 16 projecting from the corresponding wall 3, while the other member is provided with cooperating sockets or depressions 17. The dowels may be adjacent the ends of the members, as shown, as well as at other points, or they

may be more or less continuous if desired, and as may be found best.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention as defined by the appended claims.

Having thus described my invention, what I claim as new and useful and desire to secure by Letters Patent is:

A smoking device which includes a stem, such stem comprising a tubular element separable longitudinally into two substantially duplicate sep-

arable halves, each half comprising a one piece member having a flat face, each piece having a series of substantially equally spaced grooves extending inwardly from such face thus providing a series of equally spaced walls between the grooves, alternate walls being provided with relatively small ports connecting adjacent grooves at one side of the piece and the intermediate walls being provided with like ports at the opposite side of the piece, the pieces being adapted to be placed in face to face relation with the grooves and ports of one in register with those of the other, whereby there is formed a continuous tortuous smoke passage through the stem, a mouth piece on one end of the stem, and a tobacco containing element on the other end thereof.

ROSCOE C. ZUCKERMAN.
